Primary Examiner—Holly H. Baynham
Attorney, Agent, or Firm—S. Pal Asija[57] **CLAIM**

The ornamental design for a seed dispenser, as shown and described.

DESCRIPTION

FIG. 1 is a perspective view of the seed dispenser of my new design in the retracted position;

FIG. 2 is a perspective view of the seed dispenser of my new design in the seed dispensing position;

FIG. 3 is a partially broken away perspective view of my new design in the retracted position;

FIG. 4 is a top view of the seed dispenser of my new design;

FIG. 5 is a front elevation thereof;

FIG. 6 is a bottom elevation thereof; and,

FIG. 7 is a sectional view taken along line 7—7 of FIG. 4. The portion of the drawing view of FIG. 3 is shown broken away for clarity of illustration.
